William H. Boyd

BY *J. Stuart Freeman*,
ATTORNEY.

UNITED STATES PATENT OFFICE

2,457,201

FURNACE ARCH AND WALL STRUCTURE

William H. Boyd, Drexel Hill, Pa., assignor to
General Refractories Company, Philadelphia,
Pa., a corporation of Pennsylvania

Application August 13, 1943, Serial No. 498,564.

7 Claims. (Cl. 110—99)

1

The object of the invention is broadly to provide improvements in means for directly supporting the bricks which comprise the arches or roofs of furnaces from and with respect to the usual skeleton steel framework.

Another object is to provide means of this type, which can be attached to and detached from the supporting framework at will, and without the necessity of threading said means upon and longitudinally of the respective angle bars, T-bars and the like, which form elements of said framework, whereby both initial erection and repair are greatly facilitated.

A further object is to provide a form of said brick supporting means, which is particularly adapted for attachment to angle bars, of which one flange is relatively horizontal and the other relatively vertical, or which are respectively parallel with and angularly related to the plane of the supported roof.

Still another object is to provide an improved brick supporting member or hanger, by which it is possible to readily attach a brick to, or to detach such brick from a T-bar, together with details of construction by which transverse shifting of said member upon said T-bar is permitted within predetermined limits, but is prevented beyond such safe limits from becoming accidentally detached from said bar.

A still further object is to provide a brick supporting hanger of the type herein referred to, comprising a body portion having a pair of arms provided with angularly related rails adapted to engage and support one or more brick, and a pair of undercut, recessed, or hooked projections extending from said body portion in a generally opposite direction to that of said arms, one of said projections having its recess opening laterally to receive one flange of an angle bar, and the recess of the other of said projections opening towards said body portion to receive the other flange of said angle bar.

And a still further object is to provide, in combination, with a structural bar having a plurality of flanges, a brick supporting hanger comprising a pair of undercut, recessed or hooked extensions, the distance between which is sufficient to permit said hanger to be operatively attached to said bar transversely of its longitudinal axis.

With the objects thus briefly stated, the invention comprises further details of construction which are hereinafter fully brought out in the accompanying drawings, in which Fig. 1 is a perspective view of a portion of a roof structure in which various sizes and shapes of brick are shown

2

as being operatively supported by structural steel members through the medium of hangers comprising one embodiment of the invention; Fig. 2 is a side elevation of an angularly related series 5 of brick in a furnace radial nose construction with adjacent arch and wall brick, all of which are operatively supported by hangers embodying said invention; Fig. 3 is a section on the line 3—3 of Fig. 2; Fig. 4 and 5 are, respectively, top plan 10 and side elevational views of the type of hanger shown in Figs. 1 and 3; Fig. 6 shows diagrammatically a sequence of positions of said hanger, while being attached to or detached from a supporting angle bar; Fig. 7 is a fragmentary section 15 on the line 7—7 of Fig. 2 showing a modified form of hanger for nose construction.

Referring to Figs. 1, 2, 3, 4, 5 and 6, any suitable form of steel or other type of roof supporting framework is represented by an I-beam 1, to 20 which are secured at spaced intervals a plurality of angle bars 2. Said angle bars may be attached to said I-beams in any suitable manner, but are here shown as being carried by stirrup plates 3, each of which is suspended from the 25 lower flanges of said beam by four long bolts or rods 4. Such a hanging structure is especially suitable for a roof or suspended arch, but when employing the invention in the erection of a vertical wall, for instance, it obviously becomes 30 necessary to secure the angle bars more firmly with respect to the channels, I-beams, or whatever other form of structural element may be employed in the usual skeleton framework.

For purposes of illustration, the bricks comprising the roof structure represented by Fig. 1 35 are of three general standard classes; First, in the foreground are shown so-called 4½ inch arch bricks 5 and 6 (9" x 4½" x 2½"), respectively, having either one or two diagonal saw-cuts 7, and 8. Whereas the two saw-cuts 8 in the individual bricks 6 are angularly related and together form a cooperating pair of hanger-engagable, supporting surfaces 9, in the case of the single cut bricks 5 it requires two closely abutting 40 bricks with their angularly related saw-cuts 7, in order to provide the necessary pair of angularly related surfaces 10 for supporting them by engagement with the depending, angularly directed rails of the hanger. By making the rails 45 of the hanger sufficiently broad, they may be made to simultaneously support at least four of the single cut bricks, or two or more of the double cut bricks, as also indicated in Fig. 1.

To the rear of the 4½ inch brick are shown 50 horizontally extending standard 6¾ inch arch

brick 11 and 12 (9" x 6 $\frac{3}{4}$ " x 2 $\frac{1}{2}$ "), having respectively one or two diagonal saw-cuts 13 and 14, while to their rear are shown 9" arch brick 15 (9" x 6 $\frac{3}{4}$ " x 2 $\frac{1}{2}$ "), which are similar to the 6 $\frac{3}{4}$ " brick but hang vertically, and are provided with single saw-cuts 16. The upper surfaces 10 of all of the saw-cuts in said brick cooperate with and rest upon the upper diagonal surfaces of the hanger rails hereinafter described in detail.

The form of hanger shown in Figs. 1-6, comprises a centrally disposed, relatively flat body portion 17, provided with diagonally outwardly and thence inwardly converging, depending arms 18, having similarly converging, preferably transversely enlarged rails 19 having substantially planular brick supporting surfaces 20, said rails being integrally connected to said body portion through the respective arms. From the opposite side of said body portion extend a pair of undercut, recessed, or hooked, arms 21 and 22 of different lengths, and so shaped and related as to provide for the reception of the flanges 23 and 24 of an angle bar 2 between them. The shorter arm 21 is of L-shaped form and provides a recess 25 for the flange 23, while it terminates abruptly at 26 above said flange.

By contrast, the longer arm 22 comprises an inverted J-shaped extension and provides a recess 27 for reception of the angle flange 24, while it terminates abruptly in a depending hooked portion 28. By reference to Fig. 6, it will be seen that the distance between the extension terminals 26 and 28 and the depth of the respective recesses 25 and 27 is such that the hanger as a unit may be attached to the angle bar 2 transversely of the longitudinal axis of the latter. This is done by first tilting the hanger into the dot-and-dash position 29, shown in Fig. 6, then into the position 30 indicated by dashes, after which it is permitted to drop into the full line position shown. In said last mentioned position the hanger is ready to receive either single slotted or double slotted brick such as the types shown in Fig. 1. The inner or bar engaging surfaces of said arms are provided with diagonally extending shoulders or the like 26' and 28' for normally limiting the movement of the hanger transversely of the longitudinal axis of said bar.

In all forms of the hanger herein described, it should be noted that the essential characteristic of the brick supporting rails is that they have angularly related brick supporting surfaces, rather than that the entire cross sections of said rails shall conform to any definite shape or design, and that the term "angularly related" includes downwardly divergent as well as convergent brick supporting surfaces, the convergingly surfaced rails being preferred, as they tend to draw pairs of opposed bricks together, rather than to separate them, and thereby operatively supporting pairs of opposed bricks as a self-contained unit.

Referring to Fig. 2, an arch or roof of suspended straight brick 31 is shown as merging into a vertically arcuate radial nose construction, composed of radially positioned 9 inch wedge brick 32, above and forming a substantially vertical continuation of which is a wall of any desired size of straight brick 33, preferably supported independently of said nose construction, in accordance with accepted practice. For supporting said nose, there is provided a sectorial section plate 34, rigidly secured in any suitable manner to the under portion of an I-beam 35. To the curved marginal portion of said plate are bolted a series

of modified form of hanger (Fig. 7). Each of these hangers comprises an arm 36 secured at one end by a bolt 37 to said plate, while its opposite end merges integrally into a transversely elongated body portion 38, the opposite ends of which are deflected downwardly to provide divergent arms 39, terminating in downwardly converging transversely widened rails 40, the upper surfaces of which engage and support the upper surface of each pair of angularly related surfaces 41 of V-shaped cutouts 42 in the oppositely directed faces of each pair of said nose brick 32, so as to thereby provide independent, self-contained, two brick units, as illustrated.

In the appended claims, the term "roof" is used to denote the usual upright structures commonly designated as walls, and also all manner of flat, sloping, and variously curved arches, roofs and the like, to which the invention may be applicable, either in one or more of the identical forms shown or in such modifications thereof as may fall within the scope of said claims.

Having thus described my invention, what I claim and desire to protect by Letters Patent of the United States is:

1. The combination of a supporting framework, angle bars carried thereby and comprising angularly related flanges having free edge portions, and brick-supporting hangers comprising a body portion adapted to lie relatively closely parallel with one of said flanges, and spaced substantially parallel arms of unequal length having hooked ends that surround the angularly directed free edge portions of said flanges.
2. The combination of a supporting framework, angle bars carried thereby and comprising angularly related flanges having free edge portions, and brick-supporting hangers comprising a body portion adapted to lie relatively closely parallel with one of said flanges, and spaced substantially parallel arms of unequal length having hooked ends that surround the angularly directed free edge portions of said flanges, the hooked end of said parallel arm being undercut or recessed sufficiently to permit reception of the free edge portion of the parallel flange, after which by a substantially rotary movement transverse to the axis of said bar the hooked end of the other hanger arm is made to receive and surround the free edge portion of the other flange.
3. The combination of a refractory roof extending substantially in a plane, a supporting framework comprising an angle bar having its two angularly related flanges respectively substantially parallel with and perpendicular to the plane of said roof, and a brick-supporting hanger having a pair of spaced substantially parallel arms of unequal length having hooked ends that surround the free edge portions of the respective flanges of said bar.
4. The combination of a refractory roof extending substantially in a plane, a supporting framework comprising an angle bar having its two angularly related flanges respectively substantially parallel with and perpendicular to the plane of said roof, said perpendicular flange extending from said first flange away from the plane of said roof, and a brick-supporting hanger having a pair of spaced substantially parallel arms, one of which has an angular projection extending around the free edge portion of said parallel flange upon that side of said flange opposite to the supported brick, and the other arm being longer than said first arm and extending substantially perpendicular to the plane of said

roof and having a hooked terminal portion that surrounds the free edge portion of said perpendicular flange.

5. The combination of a refractory roof extending substantially in a plane, a supporting framework comprising an angle bar having its two angularly related flanges respectively substantially parallel with and perpendicular to the plane of said roof, said perpendicular flange extending from said first flange away from the plane of said roof, and a brick-supporting hanger having a pair of spaced substantially parallel arms, one of which has an angular projection extending around the free edge portion of said parallel flange upon that side of said flange opposite to the supported brick, and the other arm being longer than said first arm and extending substantially perpendicularly to the plane of said roof and having a hooked terminal portion that surrounds the free edge portion of said perpendicular flange, the interior angle of said first arm being of sufficient depth to permit said hanger to be attached to said bar by a rotary motion transverse to its longitudinal axis.

6. A refractory roof, comprising an angle bar, one flange of which extends substantially parallel with the general plane of said roof while the other flange extends angularly away from said plane, and a loosely supported brick-carrying hanger having a generally planular body portion substantially parallel with said first flange and a pair of substantially parallel arms of unequal length, the free end of the shorter arm being angular and extending around the free edge portion of said first flange, and the longer arm extending angularly away from the plane of said body portion and having a hooked free end portion that surrounds the oppositely directed free edge portion of said second flange.

7. A refractory roof, comprising an angle bar, one flange of which extends substantially parallel with the general plane of said roof while the other flange extends angularly away from said plane, and a loosely supported brick-carrying hanger having a generally planular body portion substantially parallel with said first flange and a pair of substantially parallel arms of unequal length, the free end of the shorter arm being angular and extending around the free edge portion of said first flange, and the longer arm extending angularly away from the plane of said body portion and having a hooked free end portion that surrounds the oppositely directed free edge portion of said second flange, and the surfaces of the flange-engaging portions of said arms being provided with angularly directed sections to limit the transverse movement of said hanger upon said bar when supporting brick.

20 WILLIAM H. BOYD.
